US00D923935S

(12) **United States Design Patent** (10) **Patent No.:** **US D923,935 S**
Brunner et al. (45) **Date of Patent:** **** Jul. 6, 2021**

(54) **TOOLBOX**

(71) Applicants: **KETER PLASTIC LTD.**, Herzliya (IL); **MILWAUKEE ELECTRIC TOOL CORPORATION**, Brookfield, WI (US)

(72) Inventors: **Yaron Brunner**, Gvat (IL); **Izhar Shany**, Kibutz Gvat (IL); **Uri Parizer**, Kibbutz Hukok (IL); **Ayala Vardi Bougay**, Kefar Veradim (IL)

(73) Assignees: **Keter Plastic Ltd.**, Herzliya (IL); **Milwaukee Electric Tool Corporation**, Brookfield, WI (US)

(**) Term: **15 Years**

(21) Appl. No.: **29/693,138**

(22) Filed: **May 31, 2019**

(51) LOC (13) Cl. **03-01**

(52) U.S. Cl.

USPC **D3/276**; D3/905

(58) **Field of Classification Search**

USPC D3/272, 273, 276, 279, 282, 284, 291, D3/294, 302, 900, 905, 903

CPC B25H 3/02

See application file for complete search history.

(57) **CLAIM**

The ornamental design for a toolbox, as shown and described.

DESCRIPTION

FIG. 1 is a top and front isometric view of a new design for a toolbox;

FIG. 2 is a bottom and rear isometric view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings illustrate unclaimed portions and form no part of the claimed design.

1 Claim, 8 Drawing Sheets
